APPARATUS FOR THE CONTROL OF HIGHWAY CROSSING SIGNALS

James J. Vanhorn, Swissvale, Pa., assignor to
The Union Switch & Signal Company, Swiss-
vale, Pa., a corporation of Pennsylvania

Application January 11, 1936, Serial No. 58,716
Renewed October 27, 1936

16 Claims. (Cl. 246—130)

My invention relates to apparatus controlled by a train approaching a highway crossing for governing the operation of the highway crossing signal.

5 A feature of my invention is the provision of novel and improved apparatus controlled by a train approaching a highway crossing for preventing a continued operation of the highway crossing signal in the event the train should 10 stop within the control section, and for restarting the operation of the signal when the train resumes its movement. Other features and advantages of my invention will appear as the specification progresses.

15 I will describe several forms of apparatus embodying my invention, and will then point out the novel features thereof in claims.

In the accompanying drawings, Fig. 1 is a diagrammatic view of one form of apparatus embodying my invention wherein operation of a highway crossing signal is controlled by a train approaching the intersection from one direction only. Figs. 2 and 3 are diagrammatic views of a second and a third form of apparatus, respectively, for controlling the operation of a highway crossing signal by a train approaching the intersection from one direction only, and both of which forms of apparatus embody my invention. Figs. 4, 5, 6 and 7 are diagrammatic views of 30 four different forms of apparatus for governing the operation of a highway crossing signal wherein the apparatus in each case is arranged to be effective when a train approaches an intersection from either direction, and each of which forms of apparatus also embodies my invention.

35 Similar reference characters refer to similar parts in each of the several views.

Referring first to Fig. 1, the reference characters $1a$ and $1b$ designate the rails of a stretch 40 of railway over which traffic normally moves in the direction indicated by the arrow, and which rails are intersected by a highway H . A highway crossing signal S is located adjacent the intersection. This signal S may take any one of several different forms for highway crossing signals and, as here shown, is an audible signal in the form of an electric bell. The immediate control of signal S is effected through the medium of a control relay SC the arrangement being such that when relay SC is deenergized and its back contact 4 closed current is supplied to signal S over a simple circuit and a warning is sounded. The manner of controlling the relay SC will be described hereinafter.

55 The track rails $1a$ and $1b$ are divided by in-

sulated rail joints 2 to form two track sections $3T$ and $2T$ which a train traverses in the order named in approaching the highway when traveling in the normal direction of traffic. As here shown, the exit end of section $2T$ is adjacent the highway H . The combined length of these two track sections is sufficient to provide a desired warning period for the signal S prior to the arrival of a train at the intersection when operation of the signal is initiated as the train enters the section $3T$. A wayside station RWS , such for example as a passenger or freight station, is located within the track section $3T$. Each track section is provided with a track circuit which includes a source of current such as a battery 3 connected across the rails at one end of the section, and a track relay R plus a prefix corresponding to the associated section connected across the rails at the other end of the section.

Three track instruments designated by the reference characters $M1$, $M2$ and $M3$ are operatively connected with the rail $1b$ at selected points for actuation thereof in response to the wheels of a train passing over the point at which the track instrument is located. These track instruments are each so designed that it has the characteristic of increasing its resistance in response to vibration of a train passing the location at which the instrument is attached to the rail.

These track instruments may take different forms and may be rail microphones such as disclosed and claimed in the Letters Patent of the United States No. 1,834,077, granted December 1, 1931, to A. J. Sorensen. It is deemed sufficient for the present application to point out that such rail microphone comprises an insulating housing which contains two spaced metal electrodes with carbon granules in the space between the electrodes.

When the microphone is not vibrated, the resistance between the electrodes through the carbon granules is relatively low but when the microphone is vibrated by a passing train and the carbon granules are agitated the resistance between the electrodes becomes several times the normal resistance. It will be understood, of course, that my invention is not limited to this one form of track instrument and other forms may be used.

A relay D is controlled by these track instruments and to that end is provided with a circuit extending from the B terminal of any convenient source of current, such as a battery not shown, through the electrodes and carbon granules of the track instruments $M3$, $M2$ and $M1$ in series, winding of relay D and to the opposite

terminal C of the same source of current. The parts are so proportioned that when the track instruments M₁, M₂ and M₃ are all at rest, the flow of current is sufficient to effectively energize 5 relay D and its front contact 9 is closed, but that when at least one of the track instruments is vibrated the flow of current is reduced and the relay is deenergized, or at least is not sufficiently energized, and its front contact 9 is 10 opened. Although only three track instruments are shown, it will be understood that additional instruments may be located at selected points along the track and such additional track instruments connected in the circuit of relay D should 15 it seem desirable to do so.

The signal control relay SC is normally energized over a normally closed circuit passing from the terminal B of the current source over front contacts 6 and 7 of track relays 3TR and 2TR, 20 respectively, winding of relay SC and to the opposite terminal C of the current source. An alternative energizing circuit for relay SC is provided which extends from the B battery terminal over front contact 9 of relay D, back contact 25 6 of relay 3TR, front contact 7 of relay 2TR, winding of relay SC and to the C battery terminal. It follows that when both track sections 2T and 3T are unoccupied and the track relays 2TR and 3TR are picked up, or when 30 the section 3T is occupied and section 2T is unoccupied and relay D is picked up, the relay SC is energized, but that when section 2T is occupied, or when section 3T is occupied and relay 35 D is down, the relay SC is deenergized. The relay SC is made slightly slow to pick up in character, and consequently it will not pick up in response to pulsating energy which may be supplied to it by relay D momentarily picking up when a train in section 3T is slowly passing 40 over a track instrument.

In order to describe the operation of the apparatus of Fig. 1, it will be assumed that a train enters section 3T, stops at the station RWS and then proceeds over the crossing. As 45 the train approaches section 3T, track instrument M₃ is vibrated and effects the release of relay D, instrument M₃ being preferably located just to the rear of the entrance of section 3T. When relay D releases its front contact 9 opens 50 a point in the alternative circuit for signal control relay SC. When the train enters section 3T, track relay 3TR releases and the front contact 6 opens the normally closed circuit for signal control relay SC. This latter relay accordingly releases and initiates the operation of signal S by closing back contact 4. The track relay 3TR also closes a point in the alternative circuit for relay SC at back contact 6, which circuit is now being held open at front contact 9 55 of relay D. As long as the train continues to advance the relay D will remain deenergized owing to the continued action of one of the track instruments. When, however, the train is brought to a stop at the station the active track instrument comes to rest and relay D picks up and at 60 its front contact 9 closes the alternative energizing circuit for control relay SC. Relay SC accordingly picks up and stops the operation of signal S. When the train resumes movement, 65 the track instrument in its vicinity (ordinarily the track instrument M₁) will again be vibrated and will accordingly again effect the release of relay D, with the result that control relay SC will again be released and operation of signal S 70 will again be restarted. It should be noted that the track 75

instruments are so spaced with respect to the exit end of section 3T that relay D will be maintained released until after the head end of the train enters section 2T and shunts track relay 2TR. With relay 2TR released the control relay SC will be deenergized and the signal S will be operated until the train passes over the crossing and vacates the section 2T and relay 2TR is again picked up. It is clear that when a train approaching the crossing H continues through 10 the track section 3T without stopping at the station the relay D will remain released and the signal S will continue without interruption to sound the warning.

Referring now to Fig. 2, the track circuits used are similar to those of Fig. 1. The track instruments M₂ and M₃, however, have been dispensed with and an additional relay designated SR added to take their place in the control of the relay SC. The normal energizing circuit for signal control relay SC includes front contacts 16 and 17 of track relays 3TR and 2TR, respectively; while the alternative circuit for relay SC includes the front contacts 18 and 19 of relays SR and D, respectively, back contact 16 of relay 3TR and front contact 17 of relay 2TR. The relay SR is provided with a pickup circuit passing from terminal B, through the back contact 13 of relay 3TR, back contact 18 of relay D, winding of relay SR, and to terminal C. A stick circuit for relay SR is also provided and is the same as the pickup circuit except that it includes front contact 11 of relay SR instead of back contact 18 of relay D.

When a train enters section 3T, relay 3TR releases to prepare the pickup circuit for relay SR by closing back contact 13, and at its front contact 16 opens the normal energizing circuit for relay SC, which releases and closes back contact 14 to initiate the operation of signal S. As the 40 train approaches track instrument M₁, relay D releases and completes at its back contact 18, the pickup circuit for relay SR, and at front contact 19 opens a further point in the alternative circuit for relay SC. When relay SR picks up, its front contact 11 closes its stick circuit, while its front contact 10 closes a point in the alternative operating circuit for relay SC. It will be readily seen that if the train proceeds on through section 3T into section 2T without stopping, relay D 50 remains deenergized to hold the alternative circuit for relay SC open until after it is opened at another point by the release of relay 2TR and operation of signal S under such circumstances, continues until section 2T is vacated. If, however, 55 the train stops in section 3T, the relay D picks up as soon as the track instrument M₁ comes to rest and closes the alternative circuit for relay SC at front contact 19. The relay SC accordingly picks up and stops the operation of signal S while the 60 train remains standing in section 3T. As soon as movement of the train is again started, the track instrument M₁ again becomes operative to effect the release of relay D so that the operation of the signal is again started.

In the form of the invention shown in Fig. 3, the use of relay SR has been dispensed with by dividing the former section 3T into two track circuited sections designated A₃T and B₃T, respectively. The normal energizing circuit for signal control relay SC, in this case, includes the front contacts 25, 26 and 27 of the track relays B₃TR, A₃TR and 2TR, respectively; while the alternative energizing circuit for relay SC includes the front contact 29 of relay D, back contact 26 of relay 75

A3TR, and the front contact 27 of relay 2TR. When a train enters section B3T, relay B3TR releases and at front contact 25 opens the normal energizing circuit for relay SC so that relay SC releases and closes its back contact 24 to start the operation of signal S. Just before the train enters section A3T, track instrument M1 becomes active and causes relay D to release and open a point in the alternative circuit for relay SC at front contact 29. As the train enters section A3T track relay A3TR releases, and at its back contact 26 closes a point in the alternative energizing circuit for relay SC and at its front contact 26 opens the normal circuit for relay SC. In this form of the invention, track section A3T will be relatively short, or other track instruments will be spaced along section A3T and interposed in the circuit for relay D in series with track instrument M1. It will be apparent from the foregoing that so long as the train continues moving relay D will remain deenergized and operation of the signal S will continue, but that if the train stops at the station RWS the relay D will pick up and close the alternative circuit for relay SC at front contact 29, to stop the operation of the signal during the time the train remains standing.

In Fig. 4, the circuits of Fig. 1 have been modified as required to control the operation of signal S by trains approaching the intersection from either direction. The signal control relay SC has been replaced by an interlocking relay IR, a track section 1T has been provided for the stretch of track extending to the left of the highway and a directional relay Y has been added. This track section 1T is provided with a track circuit which includes the magnet 1TR of interlocking relay IR. The track circuits to the right of the highway and the arrangement of the track instruments are similar to those of Fig. 1. The normal energizing circuit for the magnet 2TRP of relay IR passes from terminal B, through front contact 36 of relay 3TR, back contact 38 of relay Y, front contact 37 of relay 2TR, winding of magnet 2TRP, and to terminal C. An alternative energizing circuit for magnet 2TRP extends from B terminal over front contact 39 of relay D, back contact 36 of relay 3TR, and thence as before traced.

Relay Y is provided for the purpose of preventing a false operation of signal S occurring when an eastbound train, that is, a train moving from left to right in Fig. 4, has stopped in section 3T and then resumes movement. The relay Y is provided with a pickup circuit passing from terminal B, through front contacts 31 and 32 of relays D and 3TR, respectively, back contact 40 of magnet 1TR, winding of relay Y, and to terminal C. Relay Y is also provided with two stick circuits one of which includes back contact 35 of relay 2TR and the front contact 48 of relay Y, and the other of which includes back contact 45 of relay 3TR and front contact 48 of relay Y.

When a westbound train, that is, a train moving from right to left in Fig. 4, approaches the crossing, the relay Y is not energized since its pickup circuit is held open at front contact 32 of relay 3TR while the train occupies section 3T and is then held open at back contact 40 under the control of magnet 1TR of the interlocking relay as the train passes over the crossing and occupies section 1T, the contact 40 being held open due to the interlocking feature of the relay. Hence, a westbound train approaching the intersection will control the magnet 2TRP of the interlocking relay in the same manner as relay SC of Fig. 1 is controlled and operation of signal

S over back contact 44 of magnet 2TRP will be effected when the train first enters section 3T and will continue in operation without interruption until the train passes over the crossing and vacates section 2T in the event the train does not stop at the station, but if the train stops at the station RWS the relay D will be picked up and magnet 2TRP will be energized over its alternative circuit and operation of the signal S will be discontinued while the train is standing at the station, operation of the signal being restarted as soon as the train again advances. It will be understood that when a westbound train enters section 1T and magnet 1TR is released, the contact 44a will not close due to the interlocking feature of the relay and operation of the signal will not be effected as the westbound train recedes from the crossing.

When an eastbound train enters section 1T, the magnet 1TR will be deenergized and back contact 44a will be closed to initiate the operation of signal S. The back contact 40 of magnet 1TR will now be closed and complete the pickup circuit for relay Y and that relay will be picked up. When relay Y picks up it will prepare its stick circuits at its own front contact 48, and at its back contact 38 will interrupt both the normal and the alternative energizing circuits for magnet 2TRP. Magnet 2TRP will accordingly become deenergized but its back contact 44 will not close owing to the interlocking feature of the relay IR. When the train enters section 2T, the track relay 2TR will be released and at its back contact 35 will complete one of the stick circuits for relay Y. As the train enters section 3T the track relay 3TR will be released and at its back contact 45 will complete the other stick circuit for relay Y so that relay Y will be maintained energized as long as the section 3T is occupied. When an eastbound train passes over the crossing and vacates section 1T, the magnet 1TR will be reenergized and operation of the signal S will be stopped. The eastbound train upon approaching the vicinity of track instrument M1 will cause the relay D to be released but actuation of its contacts at this time will be without effect since the circuits controlled by relay D are already open at back contact 38 of relay Y and front contact 32 of relay 3TR. As soon as the eastbound train vacates section 3T, relay 3TR will pick up and at back contact 45 open the existing stick circuit for relay Y. Relay Y will accordingly release and at its back contact 38 again complete a circuit for magnet 2TRP of the interlocking relay and enable the interlocking feature of relay IR to again assume its normal position. Were the relay Y not provided, a false operation of signal S might result should an eastbound train stop at the station and then proceed out of the stretch. For example, when the train stopped at the station in section 3T the relay D would be picked up, and, with contact 38 deleted from the circuit, would have completed the alternative energizing circuit for magnet 2TRP, which would have picked up and released the interlocking feature of the relay. Then when the train resumed movement the relay D would have been again released and at its front contact 39 would have interrupted the circuit for magnet 2TRP and its back contact 44 would be closed since the interlocking feature has now been released and thus operation of signal S would result while this train moved away from the crossing out of section 3T. With the back contact 38 of relay Y included in the energizing circuits

for the magnet 2TRP, such undesired operation of signal S is prevented.

In Fig. 5, the circuit arrangement shown in Fig. 2 has been modified as required to control the 5 operation of the signal S during train movements in either direction. The interlocking relay IR and relay Y are again used in the same manner as in Fig. 4. Likewise the relay SR is used as in Fig. 2. The normal energizing circuit for magnet 2TRP of interlocking relay IR includes front contact 46 of relay 3TR, back contact 53 of relay Y, and front contact 47 of relay 2TR. This circuit will be recognized as being identical to the 10 normal energizing circuit for magnet 2TRP as used in Fig. 4. The alternative energizing circuit for magnet 2TRP of interlocking relay IR includes front contacts 50 and 49 of relays SR and D, respectively, back contacts 46 and 53 of relays 3TR and Y, respectively, and the front contact 15 47 of relay 2TR. This alternative energizing circuit for magnet 2TRP will be recognized as the same as provided for the signal control relay SC of Fig. 2, except for the inclusion of back contact 58 of relay Y. The pickup circuit for relay Y includes front contacts 51 and 42 of relays D 20 and 3TR, respectively, and the back contact 60 of magnet 1TR of the interlocking relay. While the stick circuits for relay Y include the front contact 63 of relay Y and the back contacts 55 25 and 65 of relays 2TR and 3TR, respectively. These circuits will be recognized as being similar to those provided for relay Y in Fig. 4. In view of the foregoing, it will be readily apparent that westbound trains moving through sections 3T and 2T will cause the magnet 2TRP to control the 30 operation of signal S in identically the same manner that the signal is controlled by signal control relay SC of Fig. 2, and operation of the signal will be discontinued as soon as section 2T is vacated for the reasons clearly set forth in the 40 discussion of the operation given in connection with Fig. 4. It will also be seen that as an eastbound train passes through the stretch, the relay Y will be picked up and will remain energized 45 until section 3T is vacated, and will accordingly prevent magnet 2TRP being energized by relay D picking up when an eastbound train makes a stop in section 3T. It will be evident that when an eastbound train enters section 3T the pickup circuit for relay SR will be prepared by the 50 closure of back contact 43 of track relay 3TR and will be subsequently completed at back contact 48a of relay D when the latter relay releases. The operation of relay SR at this time, however, 55 is without effect as the alternative circuit for magnet 2TRP in which front contact 58 of relay SR is included is already open at the back contact 53 of relay Y. When the train vacates section 3T, relay 3TR again picks up and at its back contacts 43 and 65 opens the stick circuits for relays SR and Y, respectively, and these relays accordingly release. When back contact 58 of relay Y again closes, the normal energizing circuit for magnet 2TRP is again established.

In the form of the invention illustrated in Fig. 6, the track circuits are identical to those employed in Figs. 4 and 5. The rail 1b of section 3T is also provided with a track instrument M1 arranged at a location opposite the station RWS as in the former arrangements, and in addition, is provided with directional track instruments TW and TE. These latter two track instruments are of the well known type which actuate their contacts as a vehicle or train passes over them in 70 one direction only. Associated with the track

instrument TW is a stick relay W having a pickup circuit which passes from terminal B through back contact 63 of relay 3TR, wires 73, 73a and 73c, contact 70 of track instrument TW closed only by trains moving in a westward direction, 10 winding of relay W, and to terminal C. The stick circuit for this relay is the same as that traced except that it includes front contact 72 of relay W instead of contact 70 of track instrument TW. A stick relay E is associated with the track instrument TE and is provided with a pickup circuit passing from terminal B through contact 62 of track instrument TE, closed only by trains moving in an eastward direction, winding of relay E, and to terminal C. The stick circuit for relay E includes back contact 63 of relay 3TR, wires 73 and 73b and the front contact 61 of relay E. The relay D is normally deenergized and is provided with an energizing circuit passing from terminal B through back contact 63 of relay 3TR, wires 73, 73a and 73c, the track instrument M1, winding of relay D, and to terminal C. The normal energizing circuit for magnet 2TRP includes front contacts 66 and 57 of relays 3TR and 2TR, respectively; while a first alternative energizing circuit for magnet 2TRP includes front contacts 71 and 69 of relays W and D, respectively, back contact 66 of relay 3TR, and front contact 57 of relay 2TR; and a second alternative energizing circuit for magnet 2TRP includes front contacts 61 and 57 of relays E and 2TR, respectively.

When a westbound train enters section 3T, track relay 3TR is released and at its front contact 66 interrupts the normal circuit for magnet 2TRP, which accordingly releases and closes the operating circuit for signal S at back contact 64. The track instruments TE, TW and M1 are positioned relatively close together along the rail 1b and track instrument M1 is vibrated and causes the release of relay D slightly before the track instrument TW is encountered and closes its contact 70, relay D having been picked up as the westbound train entered section 3T and shunted relay 3TR to close its back contact 63. Hence, the contact 69 of relay D opens the alternative energizing circuit for magnet 2TRP prior to the closing of front contact 71 of relay W when that relay is picked up over contact 70 of track instrument TW, with the result that magnet 2TRP is not energized at this time. If the train continues its movement uninterruptedly into section 2T, the track relay 2TR is released and opens the energizing circuits for magnet 2TRP at front contact 57 before relay D picks up, and, therefore, operation of signal S continues without interruption until the section 2T is vacated. Since the relay W is retained energized over its stick circuit as long as a westbound train occupies section 3T, it follows that if the train stops at the station RWS and relay D is picked up due to track instrument M1 not being vibrated the first alternative circuit for magnet 2TRP is completed and operation of signal S is discontinued as long as the train remains standing at the station, but as soon as it again advances relay D is again released with the result that operation of signal S is restarted.

When an eastbound train enters section 1T of Fig. 6, magnet 1TR releases and at its back contact 64a closes an operating circuit for the signal S. When the train enters section 2T relay 2TR releases and opens the energizing circuit for magnet 2TRP but operation of the signal S is stopped as soon as the train vacates section 1T and magnet 1TR is energized because the contact 64 con-

trolled by magnet 2TRP is held open by the interlocking feature of relay IR. When the eastbound train enters section 3T, relay 3TR releases and at back contact 66 closes a point in the first 5 alternative energizing circuit for magnet 2TRP. Relay D may pick up when the train first enters section 3T and remain energized until the train is close to the track instrument M! but the closing of front contact 69 of relay D is without 10 effect since the first alternative circuit for magnet 2TRP is held open at front contact 71 of relay W, which relay can only be energized by the closing of contact 70 of track instrument TW, and which instrument closes its contact 70 only 15 when a westbound train is moving over it. From the foregoing, it will be seen that in the absence of any control by track instrument TE, which will be shortly referred to, the magnet 2TRP remains deenergized until an eastbound train vacates section 20 3T, and, therefore, no loss of interlock of relay IR results and no false operation of signal S, such as described in connection with Fig. 4, occurs in the event an eastbound train stops at the station RWS.

25 The track instrument TE and its associated relay E are provided to prevent operation of signal S occurring in case a westbound train stops at station RWS and then backs out of section 3T. When a train moving east encounters track instrument TE its contact 62 closes the pickup circuit for relay E. Relay E on picking up completes its own stick circuit at front contact 61 and completes at its front contact 67 the second alternative energizing circuit for magnet 2TRP. Magnet 30 2TRP accordingly becomes energized when a train moving east passes the track instrument TE and releases the interlocking feature of relay IR. When a train moving east vacates section 3T the track relay 3TR again picks up and at its front contact 66 reestablishes the normal energizing circuit for magnet 2TRP and at its back contact 63 opens the stick circuit for relay E and thus the apparatus is restored to its normal position as the train moves east out of section 40 3T.

45 As previously mentioned, the instrument TE and its associated stick relay E are provided to enable a westbound train making a station stop to then back off section 3T without again initiating the operation of signal S, and this feature of my invention will now be described. When a westbound train enters section 3T and stops at station RWS, operation of signal S is discontinued in the manner already described. If now 50 this train starts to back out of section 3T track instruments M! and TE are operated, and relay D is released and opens contact 69 in the first alternative circuit for magnet 2TRP. At the same time, contact 62 of track instrument TE 55 closes the pickup circuit for relay E. Relay E picks up and at front contact 67 closes the second alternative circuit for magnet 2TRP, so that even though the first alternative circuit for this magnet is opened, its second alternative circuit is closed while section 3T is occupied and deenergizing of magnet 2TRP is prevented. Operation of signal S as a result of a westbound train backing out of section 3T is therefore avoided.

59 In the form of the invention shown in Fig. 7, the entire portion of the control territory to the right of highway H is combined into a single track section T, which is provided with one vibratory track instrument M! and two directional track instruments TW and TW!, actuated by westbound trains only. The energizing circuit for re-

lay D in this case passes from terminal B through back contact 75 of track relay TR, normally closed contact 84 of track instrument TW!, wires 83 and 83c, track instrument M!, winding of relay D; and to terminal C. The pickup circuit for relay W is the same as that traced for relay D up to wire 83c, thence through contact 80 of the track instrument TW, winding of relay W, and to terminal C. The stick circuit for relay W is the same as the pickup circuit, except that it 10 includes front contact 82 of relay W instead of contact 80 of track instrument TW. Magnet 2TRP of the interlocking relay IR is normally energized over a circuit including the front contact 76 of relay TR, and has an alternative energizing circuit including the front contacts 81 and 79 of relays W and D, respectively, and the back contact 76 of relay TR.

When a westbound train enters section T, the track relay TR releases and at its front contact 20 76 interrupts the normal circuit for magnet 2TRP, which accordingly releases and closes its back contact 76 to initiate the operation of signal S. At the same time relay D becomes energized as a result of the closure of back contact 75 of relay 25 TR and at its front contact 79 closes one point in the alternative energizing circuit for magnet 2TRP. As the train approaches the vicinity of the railway station RWS, the track instruments 30 M! and TW are operated, the track instrument M! effecting the release of relay D so that contact 79 in the alternative circuit for magnet 2TRP is again opened, while the contact 80 of track instrument TW is closed and relay W becomes energized. When relay W picks up, its 35 front contact 81 closes another point in the alternative circuit for magnet 2TRP. If the train stops before reaching the track instrument TW!, the relay D again picks up and completes the alternative energizing circuit for magnet 2TRP 40 at front contact 79, to stop the operation of signal S while the train remains standing at the station. As soon as the train resumes movement, however, the track instrument M! again becomes effective to release relay D so that operation of 45 the signal is again initiated. Before the train has receded from the track instrument M! a sufficient distance to enable relay D to again pick up, the head end of the train encounters track instrument TW! so that its contact 84 opens the 50 stick circuit for relay W. This relay accordingly releases and at its front contact 81 interrupts the alternative circuit for magnet 2TRP, so that operation of the signal S is then continued until the track section T is vacated.

55 When an eastbound train enters section 1T, magnet 1TR will release and at its back contact 74a initiate the operation of signal S in the usual manner. As soon as the train vacates section 1T, the magnet 1TR will again pick up and discontinue the operation of signal S. It will be seen that although relay D will be actuated as the eastbound train passes through section T, the operation of the relay D will exercise no control over the alternative energizing circuit for magnet 2TRP for the reason that this circuit will remain open at the back contact 81 of the relay W. It will be seen, therefore, that whether the eastbound train stops at station RWS or not, operation of signal S will not occur after section 1T 60 70 has been vacated.

65 Although I have herein shown and described only a few forms of apparatus embodying my invention, it is to be understood that various changes and modifications may be made therein 75

within the scope of the appended claims without departing from the spirit and scope of my invention.

Having thus described my invention, what I claim is:

- 5 1. In combination, a stretch of railway track intersected by a highway and including a track section equipped with a track relay, a highway crossing signal located at the intersection, a control relay for said signal, train actuated means encountered by a train approaching the intersection for modifying the condition of said control relay as required to effect the operation of said signal and to maintain the condition of 10 said control relay so modified only while movement of the train continued within said section, and means including the track relay of said section for placing said control relay under control of said train actuated means.
- 15 2. In combination, a stretch of railway track intersected by a highway and including a track section equipped with a track relay, a highway crossing signal located at the intersection, a control relay for said signal, train actuated means encountered by a train approaching the intersection for modifying the condition of said control relay as required to effect the operation of said signal and to maintain the condition of 20 said control relay so modified only while movement of the train continues, means including the track relay of the first encountered of said sections for placing said control circuits under the control of said train actuated means, 25 and a contact of the track relay of the second encountered of said sections for thereafter causing said control circuit to continue to effect the operation of said signal until the second encountered of said sections is vacated.
- 30 3. In combination, a stretch of railway track divided into a plurality of track sections each provided with a track relay and one section of which is intersected by a highway, a highway crossing signal at the intersection, a control relay for said signal normally energized over a circuit including front contacts of said track relays, a track instrument at a station location actuated only while a train in the vicinity of such location is moving, a second circuit for said control relay including a back contact of one of said track relays, and an auxiliary relay under control of said track instrument and having a contact included in said second circuit.
- 35 4. In combination, a stretch of railway track intersected by a highway and including a track section provided with a track circuit including a track relay, a highway crossing signal at the intersection, a control relay for said signal normally energized over a circuit including a front contact of said track relay, a track instrument at a station location within said stretch actuated only while a train in the vicinity of such location is moving, a second circuit for said control relay including a back contact of said track relay, and an auxiliary relay under control of said track instrument and having a contact included in said second circuit.
- 40 5. In combination, a stretch of railway track comprising two track sections each equipped with a track relay and the exit end of one section of which is intersected by a highway, a signal at the intersection having an operating circuit, a signal control relay for holding said operating circuit open and itself included in a normally closed circuit including a front contact of one of said track relays, a second circuit for said signal control relay including a front contact of one

of said track relays and a back contact of the other of said track relays, an auxiliary relay having a front contact included in said latter circuit, and a circuit for said auxiliary relay including a series of track instruments spaced along one of said sections and successively operated by a train approaching the intersection to maintain said auxiliary relay released so long as the movement of the train continues while within such section and until the train enters the other of said sections.

6. In combination, a stretch of railway track intersected by a highway and including two track sections each equipped with a track circuit including a track relay, a highway crossing signal located at the intersection, a control circuit for said signal, train actuated means encountered by a train approaching the intersection for modifying the condition of said control circuit as required to effect the operation of said signal and to maintain said control circuit so modified only while movement of the train continues, means including the track relay of the first encountered of said sections for placing said control circuits under the control of said train actuated means, 25 and a contact of the track relay of the second encountered of said sections for thereafter causing said control circuit to continue to effect the operation of said signal until the second encountered of said sections is vacated.

7. In combination, a stretch of railway track intersected by a highway and including a track section provided with a track circuit including a track relay, a highway crossing signal located at the intersection, an operating circuit for said signal, a control relay for said circuit having a normally closed circuit including a front contact of said track relay, an alternative circuit for said control relay including a back contact of said track relay closed when a train approaching the intersection enters said section, means for preventing the closure of said alternative circuit by such track relay until the head end of the train vacates said section providing the train moves uninterruptedly through said section, and other means for opening a common point in both circuits for said control relay as soon as the head end of the train vacates said section.

8. In combination, a stretch of railway track intersected by a highway and including a track section provided with a track circuit including a track relay, a highway crossing signal located at the intersection, an operating circuit for said signal, a control relay for said circuit having a normally closed circuit including a front contact of said track relay, an alternative circuit for said control relay including a back contact of said track relay closed when a train approaching the intersection enters said section, means for preventing the closure of said alternative circuit by such track relay until the head end of the train vacates said section providing the train moves uninterruptedly through said section, and other means for causing a point in said alternative circuit to be opened as soon as the head end of the train arrives at a predetermined point along said stretch.

9. In combination, a stretch of railway track intersected by a highway, a track section within said stretch provided with a track circuit including a track relay, a highway crossing signal at the intersection, a control relay for said signal normally energized over a circuit including a front contact of said track relay, a first track instrument located within said section, other

- track instruments arranged on opposite sides of said first track instrument, a first auxiliary relay under the control of said first track instrument, a second auxiliary relay placed under the joint control of said other track instruments by said track relay when said section becomes occupied and a second circuit for said control relay including a back contact of said track relay and contacts of said auxiliary relays respectively.
10. In combination, a stretch of railway track intersected by a highway, a highway crossing signal located at the intersection, an operating circuit for said signal, and train actuated means associated with a selected section of said stretch and effective when a train approaching the intersection enters said selected section for modifying the condition of said operating circuit as required to operate the signal and to maintain the condition of the operating circuit so modified only while movement of the train continues.
11. In combination, a stretch of railway track intersected by a highway, a highway crossing signal located at the intersection, an operating circuit for said signal, a first train actuated means associated with the stretch and effective when actuated by a train approaching the intersection for modifying the condition of said operating circuit as required to operate the signal, and other train actuated means associated with the stretch and effective to maintain the condition of the operating circuit so modified only while movement of the train continues.
12. In combination, a stretch of railway track intersected by a highway, a highway crossing signal located at the intersection, an operating circuit for the signal, a first train actuated means associated with the stretch and effective when a train approaching the intersection reaches a fixed point for modifying the condition of the operating circuit as required to operate the signal, and a series of train actuated devices one at each of several selected locations along the stretch and successively encountered by the train after passing said fixed point and each device effective to maintain the condition of the operating circuit so modified only when the train in the vicinity of its location is moving.
13. In combination, a stretch of railway track intersected by a highway, a highway crossing signal located at the intersection, an operating circuit for said signal, train actuated means associated with a selected portion of said stretch and effective when encountered by a train in approaching the intersection for modifying the condition of said operating circuit as required to operate the signal and to maintain the condition of the operating circuit so modified only while movement of the train continues, and other train actuated means for placing said operating circuit under the control of the first mentioned train actuated means when the train enters said selected portion of the stretch.
14. In combination, a stretch of railway track intersected by a highway, a highway crossing signal located at the intersection, an operating circuit for said signal, train actuated means associated with the stretch to one side of the intersection and effective when actuated by a train for modifying the condition of the operating circuit as required to operate the signal and to maintain the condition of the operating circuit so modified only while movement of the train continues, directional means effective when energized for preventing said train actuated means from exercising any control over the operating circuit, and means governed by a train approaching the intersection from the side opposite said one side for energizing said directional means.
15. In combination; a stretch of railway track formed into a first, a second and a third track section and each provided with a track circuit; said second section intersected by a highway, a highway crossing signal located at the intersection, a track relay for each track circuit of said second and third sections, an interlocking relay for governing the operation of the signal and having a first magnet interposed in the track circuit of the first section, a normally closed circuit for the second magnet of the interlocking relay including a front contact of each said track relay, a track instrument associated with the third section, an auxiliary relay governed by said track instrument and deenergized only when a train in the vicinity of the instrument is moving, an alternative circuit for said second magnet including a back contact of the track relay associated with the third section and a front contact of the auxiliary relay, a directional relay having a pickup circuit including a back contact of said first magnet, stick circuit means for the directional relay including back contacts of the two track relays in parallel, and a back contact of said directional relay interposed in said alternative circuit.
16. In combination, a stretch of railway track intersected by a highway, a highway crossing signal located at the intersection, a control relay for governing the operation of the signal, a first track instrument located at a station along the stretch to one side of the highway and effectively actuated only when a train in the vicinity of the station is moving, other track instruments one on each side of the first track instrument and said other instruments each effectively actuated only when a train is moving in the direction to approach the intersection, a first auxiliary relay controlled by said first track instrument and deenergized when the instrument is actuated, a second auxiliary relay controlled by said other track instruments and energized when the instrument more remote from the intersection is actuated and deenergized when the instrument nearer the intersection is actuated, and a circuit for at times governing said control relay and including a front contact of each of said auxiliary relays.

JAMES J. VANHORN.
